(57) **CLAIM**

We claim the ornamental design for a helmet, as shown and described.

DESCRIPTION

FIG. 1 is a top plan view of a helmet showing our new design;

FIG. 2 is a front elevation view thereof;

FIG. 3 is a right side perspective view thereof;

FIG. 4 is a right side elevation view thereof;

FIG. 5 is a rear and right side perspective view thereof;

FIG. 6 is a rear elevation view thereof;

FIG. 7 is a rear and left side perspective view thereof;

FIG. 8 is a left side elevation view thereof;

FIG. 9 is a front and left side perspective view thereof;

FIG. 10 is a top plan view of a second embodiment thereof;

FIG. 11 is a front elevation view of FIG. 10;

FIG. 12 is a right side perspective view of FIG. 10;

FIG. 13 is a right side elevation view of FIG. 10;

FIG. 14 is a rear and right side perspective view of FIG. 10;

FIG. 15 is a rear elevation view of FIG. 10;

FIG. 16 is a rear and left side perspective view of FIG. 10;

FIG. 17 is a left side elevation view of FIG. 10; and,

FIG. 18 is a front and left side perspective view of FIG. 10.

The details shown in broken lines form no part of the claimed design.

1 Claim, 18 Drawing Sheets
